CLAIM

The ornamental design for a semi-automated device for products and methods for single parameter and multiparameter phenotyping of cells, as shown and described.

DESCRIPTION

FIG. 1 is a front perspective view of our new design;
FIG. 2 is a rear perspective view thereof;
FIG. 3 is a top view thereof;
FIG. 4 is a front view thereof;
FIG. 5 is a rear view thereof;
FIG. 6 is a bottom view thereof;
FIG. 7 is a right side view thereof; and,
FIG. 8 is a left side view thereof.

The broken lines in the drawing views are included for the purpose of illustrating portions of the semi-automated device that form no part of the claimed design.
